UNITED STATES PATENT OFFICE.

CLIFTON D. PETTIS, OF NEW YORK, N. Y.

MOLD.

Original application filed November 3, 1924, Serial No. 747,481. Divided and this application filed April 1, 1925. Serial No. 19,811.

To all whom it may concern:

Be it known that I, CLIFTON D. PETTIS, a citizen of the United States, residing at New York, county of New York, and State 5 of New York, have invented a new and useful Improvement in Molds, of which the following is a full, clear, and exact description.

The present invention relates broadly to molds of the character adapted for the production of metal castings and to improved 10 operating mechanism for opening and closing the mold members.

At the present time it is customary in the art to which the present invention relates 15 to construct molds with a plurality of relatively movable members mounted for movement about predetermined axes, with operating mechanism for moving such mold members to and from closed position. Ordinarily, the form of operating mechanism provided has either been such as to require a considerable period of time to effect complete movement of the members, or has been such that an abrupt opening and closing 25 has been accomplished.

I have found that it is desirable to provide mold operating mechanism of such character that the members operated thereby may be moved positively and quickly from 30 one position to another, the movement being effected under such conditions that locking of the members in closed position is insured. In certain types of molds, it is necessary to effect a comparatively wide opening movement of the members so as to completely 35 clear the castings formed therein. Frequently the molds in which this type of movement is required are of comparatively small over-all dimensions, thereby limiting 40 the character of the operating mechanism which can be employed.

The present invention has for certain of its objects the provision of mold operating mechanism of such nature that it will effect 45 a positively smooth movement of the mold members in both directions, with a possibility of a wide opening movement of the members and a locking of the members in closed position.

50 In the accompanying drawings there are shown, for purposes of illustration only, one embodiment of the present invention, it being understood that the drawings do not define the limits of my invention, as changes 55 in the construction and operation disclosed therein may be made without departing

either from the spirit of the invention or the scope of my broader claims.

In the drawings:

Figure 1 is a side elevational view, largely 60 diagrammatic, illustrating one form of mold and operating mechanism embodying the present invention; and

Figure 2 is an end elevation, partly broken away and partly in section, of the structure 65 illustrated in Figure 1.

In carrying out the present invention, there may be provided a suitable mold base, 70 2 having bearing brackets 3 carried thereby for the reception of a longitudinally extending pivot pin 4.

Cooperating with the pivot pin is a plurality of mold members 5, each preferably having downwardly extending lugs 6 for cooperation with the pivot 4, whereby during either opening or closing movement the members will swing about the pivot as an axis. For limiting the relative closing movement of the mold members 5, they may be provided on either one or both ends 80 thereof with stops 7 adapted to cooperate with a centering projection 8 extending upwardly from the base and conveniently formed integral with the end brackets 3.

Each of the mold members may conveniently comprise a metal box-like frame, as clearly indicated in Figure 2, adapted to receive therein matrix forming members 9 of any desired construction and contour, depending upon the character of the casting 90 to be formed. The outer wall of each of the mold members is provided with a pair of integral fork shaped projections arranged adjacent the ends of the mold members and having upper and lower arms 10, the inner 95 parallel faces of which are adapted to be engaged by a pair of circular cams or eccentrics 11. These cams or eccentrics are mounted on arms 12 pivotally connected by pivot pins 13 to lugs 14 that project upwardly from the outer side edges of the base 2. Preferably, the arms 12 constitute the end members of a bail having a horizontal member 15, the member 15, the eccentric 11 and the arms 12 all being preferably cast 105 integral to provide a unitary operating structure.

As clearly shown in Figure 2, each bail fits between the upper ends of the lugs 14, and the pivot pins 13 are journaled in the upper ends of these lugs and are threaded into openings formed in the lower portions 110

- of the bail arms 12. The horizontal member 15 of each bail may be provided with a central socket 16 in which is fixed a handle 17 for swinging the cams upon the pivot pins 13. Obviously, as the cams are rocked upon the pivot pins they will cooperate with the upper arms 10 of the mold members to move the latter to closed position, and with the lower arms 10 to open the mold members. As the cams are swung to close the mold members, they move toward a dead center position vertically above their pivots so that they serve not only to open and close the mold, but also to lock it in closed position. Preferably, as shown in Figure 2, the arrangement is such that when in closed position the cams will not quite have reached their dead center position, and therefore can be employed to force the meeting faces of the mold members into snug engagement, take up wear between the contact surfaces of the operating parts and also lock the mold members in closed position.
- I have found that in actual practice further desirable results are obtained by providing spaced operating cams for each of the mold members, whereby at least a dual point of contact with each of the members is insured, thereby preventing any spring or undesirable spreading of the parts such as would result in the production of imperfect castings by reason of the formation of fins, or the like, thereon. Frequently, it is desirable to open the mold members to an extent greater than that which would ordinarily be permitted by the diameter of the cams 11, and in order to overcome this limitation and avoid undue spacing of the arms 10, the pivotal axes of the cams formed by the pins 13 are preferably located outside of the peripheries of the cams, whereby a much greater opening movement is made possible than can be obtained where the axes are located within the peripheries of the cams. This operation not only permits easy removal of a casting but also affords ready access to the matrix forming surfaces for cleaning and coating thereof, as may be required, as well as permitting the insertion of cores.
- The gradual curvature of the cams cooperates with the arms 10, not only to produce a positive movement of the mold members but also to produce a smooth gradual movement thereof, the speed of which may be varied directly in accordance with the speed at which the handles 17 are operated, without any danger of sudden jars or abrupt movements of the members.
- The present application is a division of my copending application Serial No. 747,481, filed November 3, 1924.
- The advantages of the present invention arise from the provision of eccentric operat-

ing means whereby mold members may be smoothly and positively moved to the different positions required.

Further advantages arise from the utilization of a plurality of cams for each of the mold members, as well as from the positioning of the pivotal axes of the cams outside of the cam peripheries.

I claim:

1. In a casting mold, a movable mold member, and a cam for moving said member, said cam having its pivotal axis outside of the periphery thereof, substantially as described.

2. In a casting mold, a movable mold member, and a cam for moving said member, said cam having its pivotal axis outside of the periphery thereof and being effective for holding said member in the closed position to which it is moved, substantially as described.

3. In a casting mold, a base, a plurality of mold members movably mounted on said base, cam engaging means on said members, rocking cams engaging said means to open and close the mold members, and a stop limiting the closing movement of said members for properly centering the members in closed position, substantially as described.

4. In a permanent casting mold, the combination of a base, a horizontal pivot pin thereon, a plurality of mold members having depending lugs engaging said pivot pin to swing to and from vertically closed position, rocking bail having horizontal axes mounted on the base outside of said members, eccentric cams on said bail, and means on said members embracing said cams, substantially as described.

5. In a permanent casting mold, the combination of a base, a plurality of mold members pivotally mounted on said base and having outwardly projecting lugs, rock arms on said base, and eccentric cams on said arms engaging said lugs for opening and closing said members, substantially as described.

6. In a permanent casting mold, the combination of a base, a plurality of mold members pivotally mounted on said base and having outwardly projecting lugs, rock arms on said base, and eccentric cams on said arms engaging said lugs for opening and closing said members, the pivotal axes of said rock arms lying outside the peripheries of said cams, substantially as described.

7. Mold operating means, comprising spaced cams, pivotal mountings for said cams, and a common actuating means for a plurality of spaced cams, the pivotal mountings for said cams being outside of the peripheries thereof, substantially as described.

8. In a mold, a movable mold member, operating means therefor comprising a rock.

ing cam having its rocking axis outside of the periphery of said cam, and operating means for said cam, substantially as described.

- 5 9. In a mold, relatively movable mold members, a pair of spaced lugs projecting outwardly from each of said members, a cam positioned between said lugs, a pivotal mounting for said cam, and operating means
- 10 for said cam, the pivotal mounting for said cam being outside of the periphery thereof, substantially as described.
11. In a casting mold, a base, a mold member movably carried thereby, a second mold member with which the movable mold member cooperates, a cam for operating said movable member, said cam being so dimensioned and mounted as to exert a pinch-

ing action between the mold members at all times when in closed position, and effective for locking said movable member against accidental opening movement, substantially as described.

- 12 11. In a casting mold, a base, a plurality of mold members movably carried thereby, a cam for operating each of said members, said cams being so dimensioned and mounted as to exert a pinching action on the mold members at all times when in closed position to lock said members against accidental opening movement, and means for operating any one of said cams independently of the others, substantially as described.

In testimony whereof I have hereunto set my hand.

CLIFTON D. PETTIS.
